SEPARATION OF XYLENE FROM HYDRO-CARBON MIXTURES

Charles R. Clark, Springfield Township, Montgomery County, Pa., assignor, by mesne assignments, to Allied Chemical & Dye Corporation, a corporation of New York

Application December 3, 1940, Serial No. 368,315

8 Claims. (Cl. 202—42)

This invention relates to a process for recovering xylene hydrocarbons from mixtures containing them together with other hydrocarbons. In this specification and the appended claims the term "xylene" is used in its comprehensive meaning as referring to aromatic compounds of the benzene series boiling in the range of temperatures at which the several xylenes boil. The term as thus used includes the three xylenes: ortho, meta and para, and ethyl benzene.

Numerous hydrocarbon oils are known which contain xylenes in varying proportions. For example, gasoline fractions obtained by the distillation of certain types of petroleum frequently contain substantial proportions of xylene, although mainly consisting of other hydrocarbons. Oils of petroleum origin having a considerable content of aromatics, including xylene, may be treated by well known selective solvent processes to produce fractions rich in aromatics; for example, extraction of suitable fractions of such petroleum oils with sulfur dioxide may yield fractions of increased xylene content. In such cases xylene is accompanied by non-aromatic oils which may be largely paraffinic, naphthenic or olefinic in character. A considerable portion of these oils cannot be completely separated from the xylene by direct fractional distillation because of the closeness of their boiling points to that of xylene or because they form constant boiling mixtures with xylene. Furthermore, while ordinarily xylene may be separated by direct fractional distillation from light oils produced by the gasification of coal, in some cases the xylene is accompanied by difficultly separable non-aromatic oils of the same general character as described, owing to carbonization conditions, type of coal used or other special circumstances. Also synthetic hydrocarbon gas mixtures produced by various catalytic processes may contain xylene which, when recovered, is accompanied by similar difficultly separable constituents.

By fractional distillation of these oils containing xylene, fractions of increased xylene content may be obtained. These xylene fractions, however, will still contain large amounts of the other constituents of the oil having boiling points in the neighborhood of the boiling point of xylene or forming mixtures of constant boiling points in the range of temperatures at which xylene distills from the oil. The fact that the oils containing xylene have generally a relatively low content of xylene makes it particularly difficult to recover by fractional distilla-

tion or selective solvent extraction or a combination of both of these procedures a xylene product of a high degree of purity. Accordingly, recovery of xylene of a relatively high purity from these sources presents a difficult problem of great industrial importance.

For many purposes to which xylene is put, it is desirable to use as pure a material as may be economically available. Direct fractional distillation, because of the difficulties pointed out above, will not effect a recovery of pure xylene from oils such as enumerated and in many cases will not give fractions of suitably high xylene content or free from materials which even in small concentrations adversely affect chemical treatment of the xylene or the products produced therefrom.

It is an object of this invention to provide a process for azeotropically distilling the xylene-containing oil in the presence of an azeotropic agent which is particularly effective for separating the xylene from like-boiling, non-aromatic compounds contained in the oil to obtain a commercially pure xylene fraction.

It is a further object of the invention to provide a process for the separation of xylene from fractions of petroleum oil containing xylene and other hydrocarbons of similar boiling range.

In accordance with this invention, xylene in any desired degree of purity is separated from an oil containing it and other hydrocarbons boiling over the same temperature range as xylene by subjecting the oil to azeotropic distillation with rectification of the vapors in the presence of allyl alcohol. For optimum results in the production of xylene of high purity, the rectification should be carried out so as to maintain a temperature at a point in the zone where rectification of the oil vapors takes place, not exceeding 97° C., preferably within the range of 94° to 97° C. The distillation in the preferred embodiment of the invention is continued in the presence of allyl alcohol in the rectification zone until said temperature at said point is reached, at which point the residue will contain at least 95 parts by weight of xylene to every part by weight of other hydrocarbons which distill in the same temperature range as xylene and then interrupted, or continued and the distillate collected separately from the distillate obtained by condensing vapors driven off while the temperature in the rectification zone is below said temperature. By operating in accordance with these conditions, a xylene of high purity, after removal of allyl alcohol by any desired means, may be

obtained as a residue in the still or as the separately collected distillate, the purity being improved the closer said temperature is maintained to 97° C.

The xylene-containing oils treated in accordance with my invention, are first preferably fractionally distilled to produce a fraction boiling within the temperature range 125° to 150° C., for example 136° to 144° C. The fractions utilized preferably contain little, if any, hydrocarbons distilling from the hydrocarbon xylene fraction at temperatures materially above those at which xylene distills therefrom. However, oil fractions containing higher boiling materials than xylene may be utilized so that such materials remain with the xylene residue at the conclusion of the azeotropic distillation of the xylene fraction to remove hydrocarbons of similar boiling range and after the azeotropic distillation is complete, xylene may be separated from the higher boiling hydrocarbons by fractional distillation in the absence of an azeotropic agent.

Furthermore, in some cases low boiling hydrocarbons may also be present in the xylene fractions subjected to azeotropic distillation. Such low boiling materials may be separated from the xylene by the azeotropic distillation itself. Nevertheless, the presence of such low boiling materials requires the use of larger amounts of allyl alcohol to obtain a xylene product of given purity and, hence, I preferably utilize fractions boiling within the range of 125° to 150° C. because such fractions may ordinarily be azeotropically distilled to produce commercially pure xylene with a minimum of the allyl alcohol azeotropic agent.

The ratio of allyl alcohol to the xylene fraction which may be employed in carrying out this invention depends upon the amount and nature of the hydrocarbon impurities in the xylene fraction, the purity desired in the xylene residue from the distillation, the proportion of xylene in the original xylene fraction which is to be recovered in the residue, the procedure used for distillation of the allyl alcohol-xylene mixture, and the equipment employed. The quantity of allyl alcohol used in the distillation of hydrocarbons from a given quantity of xylene fraction should be in excess of that which will form azeotropic mixtures with the non-xylene hydrocarbons which are to be vaporized and taken over into the distillate. By returning most or all of the allyl alcohol collected from the distillate to the still, for example, as reflux liquid, the total amount of allyl alcohol necessary to effect separation of the non-xylene constituents and the xylene will be materially reduced. If desired, fresh allyl alcohol may be introduced into the xylene fraction being distilled during the course of the distillation; also the allyl alcohol separated from the distillate may be returned continuously or periodically to the still or rectification column while the distillation of the xylene fraction is progressing.

Regulation of the temperature in the rectification of the vapors so as to maintain the control temperature not above 97° C., preferably within the range of 94° to 97° C., is accomplished by maintaining an adequate quantity of allyl alcohol in the still or rectification column, or both, during the distillation of the xylene fraction to selectively carry over through the rectification treatment the vapors of the hydrocarbons to be removed from the xylene. As the distillation proceeds, temperature readings are

taken at the top of the rectification column and by supplying additional allyl alcohol when required to prevent this temperature from rising above 97° C. an adequate amount of allyl alcohol will be present during the separation of the non-xylene hydrocarbons from the xylene fraction. It is not necessary that this point of control temperature be at the top of the column although this is a satisfactory point for determining this temperature. One skilled in the distillation art will recognize suitable points for maintaining this control temperature in any specific apparatus according to well known distillation principles.

5 When the azeotropic distillation of the xylene fraction has been carried to the point at which the residue containing xylene has the desired purity with respect to hydrocarbons of similar boiling range to xylene, the residue may be purified further to remove any allyl alcohol it contains and to remove any other impurities present. For example, when the distillation is carried to the point at which the xylene constitutes substantially 95 per cent or more of the 10 total hydrocarbon content of the residue, the residue may be washed with water to remove the allyl alcohol remaining in the oil and then given a conventional sulfuric acid wash to further purify the xylene, and redistilled.

15 20 25 30 35 40 45 50 55 60 65 70 75 80 85 90 95 100 My invention will be described in more detail in connection with the accompanying drawing showing diagrammatically apparatus suitable for carrying out the invention and in the following example.

35 The apparatus of the drawing comprises a still 1 provided with a heater 2 and connected with a rectification column 3 and a condenser 4 for the vapors leaving the top of the column. By means of valves 5 and 6, condensate flowing from condenser 4 is divided in controlled proportions, one part of the condensate being returned through pipe 7 to the top of column 3 and refluxed in contact with the vapors rising in the column and the other portion of the condensate being withdrawn through pipe 8. Three receivers 9, 10 and 11 are connected to pipe 8 through valve-controlled branch pipes 12, 13 and 14 so that the condensate drawn off through pipe 8 may be divided and distributed as described below to the several receivers.

40 Receiver 10 is connected by a pipe 15 controlled by valve 16 with a second still 17. Still 17, like still 1, is provided with a heater 18, a rectification column 19, a condenser 20 and pipes 21 and 22 controlled by valves 23 and 24 for return of determined proportions of condensate from condenser 20 to the top of column 19 and withdrawal of the remainder of the condensate through pipe 22. Pipe 22 leads to a separator 25 into which water may be introduced from a pipe 26.

45 In carrying out one embodiment of my invention, in the apparatus described above, a petroleum oil produced by catalytic treatment of a petroleum distillate in the presence of hydrogen was a crude material from which the xylene is recovered. This oil had the following characteristics:

70	Specific gravity at 15.5° C.	0.780
	Aromatics	per cent 47.5
	Francis bromine No.	0.05
	Distillation:	
	Start	degree C. 44
	End	do 210

The charge of this hydrocarbon mixture introduced into still 1 was boiled in the still and the evolved vapors were counter-currently contacted in column 3 with reflux condensate from condenser 4, in which the vapors leaving the top of the column were substantially entirely condensed. Most of the condensate from condenser 4 was returned through valve 5 and pipe 1 to furnish the reflux to the top of the column. The remaining small portion of the condensate is continuously withdrawn through valve 6 and pipe 8 and is passed into collecting vessel 9. The distillation was conducted under substantially atmospheric pressure; i. e., the pressure in condenser 4 and at the top of column 3 was substantially atmospheric and the pressure in still 1 was only enough higher to force the vapor through the rectification column to the condenser.

When the vapor temperature in the top of column 3 reaches 125° C., the condensate passing through pipe 8 is diverted to vessel 10. The cut taken in vessel 10 includes the distillate coming over up to and at a temperature of 150° C. at the top of the column. Thereafter the condensate passed forward through pipe 8 is collected in vessel 11 and the distillation is continued as long as may be desired. The cuts in vessels 9 and 11 contain low and high boiling fractions of the original oil. They may be treated or used in any desired manner. If desired, instead of taking off a high boiling fraction and collecting it in vessel 11, when the desired fraction has been collected in vessel 10 the distillation may be discontinued and the residue left in the still may be withdrawn therefrom.

With efficient rectification of the vapors in column 3 during the fractional distillation of the crude xylene oil, the cut collected in vessel 10 may contain about 54 per cent by weight of xylene, as determined by the specific dispersion method for analyzing hydrocarbon oils described in Industrial & Engineering Chemistry, Analytical Edition, vol. 11, page 614, November 15, 1939.

The xylene fraction collected in vessel 10 is subjected to azeotropic distillation which represents the second stage of this example. For this purpose the xylene fraction containing 54 per cent of xylene was introduced in still 17 together with anhydrous allyl alcohol in the proportions of 333 volumes of allyl alcohol for every 150 volumes of the xylene fraction. The mixture of allyl alcohol and xylene fraction was distilled with rectification of vapors in column 19 and condensation of the vapors leaving the top of the column in condenser 20. Most of the condensate was returned through pipe 21 to the top of column 19 while the remainder was withdrawn by pipe 22 through the separator 25.

Azeotropes formed with allyl alcohol by the hydrocarbons other than xylene present in the xylene fraction introduced into still 17 have boiling points sufficiently below that of the xylene for them to be preferentially vaporized and by rectification in column 19 to be largely separated from any xylene which is vaporized in still 17 and enters column 19, so long as there is sufficient allyl alcohol present in the vapor and liquid phases in the rectification column. The non-xylene-allyl alcohol azeotropes contain the allyl alcohol in the proportion of not more than 2 parts of alcohol to each part of oil. As pointed out above, the requisite quantity of allyl alcohol to be supplied is that which will maintain the temperature at a point in the rectification col-

umn, preferably at the top of the column not above 97° C. In this example, the requisite quantity of allyl alcohol was supplied in the initial charge to the still. The alcohol was vaporized from the still, entered the rectification column as vapor and in part was returned to the column as liquid in condensate from condenser 20.

If insufficient allyl alcohol is initially introduced in the charge to the still, additional alcohol sufficient to maintain the requisite temperature in the rectification column may be supplied as the distillation progresses. This allyl alcohol may be introduced either into the still or into the rectification column itself.

15 The xylene was in large part returned down the rectification column and retained in the still while the azeotropes of the allyl alcohol with the other hydrocarbons were distilled out and were collected in separator 25. The loss of xylene from the still to the condensate drawn off through pipe 22 will depend upon the efficiency with which the vapors are rectified. Sufficient rectification is employed in order to keep down this loss of xylene.

20 In carrying out the process of this example, as the distillation continued the temperature of the vapors at the top of column 19 rose from 80.8° to 96.6° C. and thereafter rose to 137.9° C. The xylene content of the oil obtained from the condensate withdrawn through pipe 22 by washing the condensate with water to free it of allyl alcohol increased from less than 5 per cent to more than 97 per cent before the temperature at the top of the column rose above 96.6° C. The oil obtained from the condensate collected while the temperature was rising from 96.6° to 137.9° C. was approximately 100 per cent xylene. The distillation was discontinued when the temperature of the vapors at the top of column 19 reached 137.9° C. and the oil content of the residue left in the still was substantially 100 per cent xylene; the xylene distilled over as the temperature rose from 96.6° to 137.9° C., combined with the xylene residue left in the still, represented a yield of more than 75 per cent of the xylene in the original xylene cut as 100 per cent xylene.

25 By agitating the distillate collected in separator 25 with water and allowing the liquid to remain quiescent for a short time, it separates into two layers. The upper layer is an oil containing the non-xylene constituents of the xylene fraction supplied to still 17 and a portion of the xylene carried over in the distillation. This oil may be treated or used as desired. By separately recovering and treating the distillate in two portions, two oil fractions may be obtained, one low in xylene which may be added to xylene oil distilled in still 1 and a second oil fraction high in xylene which may be introduced into the xylene fraction from vessel 10 and redistilled with this fraction in a subsequent distillation in still 17. By thus reworking the distillate, the xylene it contains may be recovered. The aqueous allyl alcohol layer separated in treating the distillate with water may be treated in any of the well known manners to recover anhydrous allyl alcohol therefrom and this alcohol utilized in distilling a subsequent batch of xylene fraction.

30 While I have described my process in conjunction with examples in which the two distillation steps are batch procedures, either or both of these distillations advantageously may be carried out continuously by well-known continuous distilla-

tion procedures suitable for the fractional distillation of mixtures of two or more liquids.

It is, of course, obvious preliminary distillation of a crude xylene oil to obtain a xylene fraction suitable for recovery of xylene therefrom by azeotropic distillation with allyl alcohol need not be carried out in immediate conjunction with the azeotropic distillation of the xylene fraction. The xylene fraction suitable for treatment by the azeotropic distillation step of my process may be produced in one plant, transported to and treated later in another plant to distill it with the allyl alcohol. Nor is my invention limited to any particular procedure for the production of the xylene fraction. My invention contemplates the distillation with the above described allyl alcohol, of any oil fraction containing materials distilling in the range of 125° to 150° C., preferably 136° C. to 144° C. and containing xylene hydrocarbons together with other hydrocarbons which, when the oil is distilled, vaporize therefrom in the same temperature range as the xylene and, therefore, are not separable from the xylene by direct fractional distillation. As used in this specification and the appended claims, the term "xylene fraction" refers to all such xylene-containing oils, whether produced by fractional distillation of xylene-containing materials or by any other means.

In this specification I have described the azeotropic distillation of xylene fractions as carried out under substantially atmospheric pressure and the temperatures given in the specification and claims are for such pressure. It is, of course, possible to distill the xylene fraction with the alcohol under pressures above or below atmospheric. In that case, the temperatures in the azeotropic or non-azeotropic distillation used in carrying out the process of my invention will differ from the temperatures given herein for atmospheric pressure but will differ in amounts corresponding to the changes in temperature due to the change in pressure.

Reference is made to my copending application Serial No. 361,825 of October 19, 1940, in which I have disclosed and claimed a process for separating xylene from like-boiling hydrocarbons involving azeotropic distillation of oil fractions in the presence of water and a saturated mono-hydroxy aliphatic alcohol of low molecular weight.

What is claimed is:

1. A process for the treatment of a xylene fraction to separate the xylene from other hydrocarbons of the group consisting of paraffinic, olefinic and naphthenic hydrocarbons contained therein which distill from the xylene fraction in the same temperature range as the xylene distills therefrom which comprises distilling said xylene fraction and rectifying the vapors evolved therefrom in the presence of sufficient allyl alcohol to effect separation of a substantial amount of said other hydrocarbons from said xylene, thereby leaving a residue enriched in xylene.

2. The process for the recovery of xylene from an oil containing it with non-aromatic hydrocarbons of the group consisting of paraffinic, olefinic and naphthenic hydrocarbons which comprises fractionally distilling said oil, recovering by the fractional distillation a fraction containing xylene and non-aromatic hydrocarbons which distill from said xylene fraction in the same temperature range as the xylene distills therefrom, distilling said xylene fraction and rectifying the vapors evolved therefrom in the pres-

ence of allyl alcohol in amount sufficient to effect vaporizing and removing from the xylene of azeotropes of said non-aromatic hydrocarbons boiling in the same temperature range as the xylene.

3. The process for the recovery of xylene from an oil containing it with non-aromatic hydrocarbons including paraffinic hydrocarbons and which may include olefinic and naphthenic hydrocarbons which comprises fractionally distilling said oil, recovering by the fractional distillation a fraction boiling within the range of 125° to 150° C. containing xylene and non-aromatic hydrocarbons which distill from said xylene fraction in the same temperature range as the xylene distills therefrom, distilling said xylene fraction and rectifying the vapors evolved therefrom in the presence of allyl alcohol in amount sufficient to effect vaporizing and removing from the xylene of azeotropes of said non-aromatic hydrocarbons boiling in the same temperature range as the xylene.

4. A process for the treatment of a xylene fraction containing xylene and paraffinic hydrocarbons, and which may contain olefinic and naphthenic hydrocarbons, to separate the xylene from said other hydrocarbons contained therein which distill from the xylene fraction in the same temperature range as the xylene distills therefrom, which comprises distilling said xylene fraction and rectifying the vapors evolved therefrom in the presence of allyl alcohol while maintaining at a point in the rectification zone a temperature not above 97° C. by maintaining the presence of said allyl alcohol at said point and continuing the distillation until the unvaporized residue of the distillation contains at least 95 parts by weight of xylene to every 5 parts by weight of other hydrocarbons which distill from a mixture of xylene and hydrocarbons in the same temperature range as the xylene, thereby vaporizing and removing from the xylene fraction other hydrocarbons present therein which distill therefrom in the absence of allyl alcohol in the same temperature range as xylene.

5. The process for the treatment of an oil fraction boiling within the range of 125° to 150° C. containing xylene and non-aromatic hydrocarbons including paraffinic hydrocarbons and which may contain olefinic and naphthenic hydrocarbons boiling in substantially the same temperature range as xylene which comprises fractionally distilling said xylene fraction in the presence of allyl alcohol in amount sufficient to effect vaporizing and removing from said fraction of the azeotropes of non-aromatic hydrocarbons present therein which distill therefrom in the absence of said allyl alcohol in the same temperature range as the xylene and leaving a hydrocarbon residue of the distillation enriched in xylene.

6. The process for the recovery of xylene from a xylene oil fraction boiling in the range of 125° to 150° C. containing xylene and paraffinic hydrocarbons and which may contain olefinic and naphthenic hydrocarbons boiling in the same temperature range as said xylene, which comprises fractionally distilling said fraction and rectifying the evolved vapors in the presence of allyl alcohol in amount such that the temperature of the vapors at a point in the rectification zone does not exceed about 97° C., thereby vaporizing and removing from the xylene fraction hydrocarbons which distill therefrom in the absence of allyl alcohol in the same temperature range as the xylene contained therein.

7. The process for the recovery of xylene which

comprises azeotropically distilling in the presence of allyl alcohol a xylene oil fraction containing xylene and non-aromatic hydrocarbons including paraffinic hydrocarbons and which may include olefinic and naphthenic hydrocarbons boiling in the absence of said allyl alcohol in the range of 125° to 150° C. while rectifying the vapors in the presence of said allyl alcohol until a temperature within the range of 94° to 97° C. is reached at a point in the rectification zone, thereby vaporizing and removing as distillate non-xylene hydrocarbons present in the fraction.

8. The process for the recovery of xylene which comprises azeotropically distilling in the presence

of allyl alcohol a xylene oil fraction containing xylene and non-aromatic hydrocarbons including paraffinic hydrocarbons and which may include olefinic and naphthenic hydrocarbons boiling in the absence of said allyl alcohol in the range of 125° to 150° C. while rectifying the vapors in the presence of said allyl alcohol until a temperature within the range of 94° to 97° C. is reached at a point in the rectification zone, thereby vaporizing and removing as distillate substantially all of the non-xylene hydrocarbons present in the fraction and leaving a hydrocarbon residue, the oil content of which is about 95 per cent xylene.

CHARLES R. CLARK.
